EXPANSION JOINT

John Foster Oury, Chicago, Ill.

Application March 17, 1937, Serial No. 131,281

5 Claims. (Cl. 72—106)

My invention relates to expansion joints for concrete structures and the like, and has particular reference to an expansion joint which is fashioned from a single unitary flat piece of flexible material of suitable width and length, and which is bent at some point intermediate its length so its end portions are at an angle to each other and is used in sections of concrete making angular turns, thereby providing an expansion joint for turns or corner constructions which is not subject to breakage or leakage as is common with expansion joints now in use.

Another and further object of my invention is the provision of an expansion joint made from a single sheet of foldable material, such as copper, which can be bent to form a right angle turn and embedded in a concrete structure, thus providing a leakproof joint in the structure and which prevents moisture from passing through the walls of the structure, such as a wall, floor or ceiling, and also in trenches, conduits, tunnels, reservoirs, swimming pools, and the like.

In practice the making of flumes, reservoirs, swimming pools, basements or any concrete structure subject to hydrostatic pressure, the concrete itself can be coated in such manner that it is impervious to water, but due to the expansion and contraction of the concrete, expansion joints must be used between the sections making up the walls of the concrete structure. These expansion joints are made in various types and forms and when necessary to provide an expansion joint for a bend in concrete structures or a right angle turn in concrete walls, the expansion joint has been made from metal and bent to form with the ends soldered together to form a unitary structure. Due to the strains imposed upon the soldered metal after the structure is in service, the solder breaks away, thereby permitting moisture to leak through the joint, destroying its usefulness and effectiveness in preventing moisture from passing through the structure at the joints. As a result these structures begin leaking, and being embedded in concrete it is extremely difficult, if not impossible, to repair such leaks. In some cases they cannot be repaired at all, and as a result such structures are oftentimes defective.

In my improved structure a single unitary section of flexible material, such as copper, is bent around a corner and embedded in the concrete structure so that no solder is used. In view of the fact that the expansion joint at the corner is continuous and the material is unbroken, there is not the stress and strain put upon it in the

same manner that a soldered joint would receive, and therefore this kind of expansion joint has proven effective in service in preventing leaks through concrete walls, flumes, and the like, and preserving the concrete structure from the development of leaks at the corners or where the concrete wall changes its direction.

Another and further object of my invention is the provision of a concrete joint which can be easily and quickly shaped to form angles or the like, through the use of proper tools on the job of filling or laying the concrete and in this manner the proper angles, thickness and so forth, can be procured to fit any particular job.

Another and further object of my invention is the provision of a concrete joint which can be also placed in flat slabs of concrete so that moisture is prevented from passing therethrough when used for road work. In this manner the concrete slabs are preserved from the action of freezing and an effective joint is provided which preserves the concrete and at the same time prevents moisture from passing through the joints between the concrete slabs.

These and other objects of my invention will be more fully and better understood by reference to the accompanying sheets of drawings, and in which—

Figure 1 is a perspective view of a portion of a concrete structure showing my improved expansion joint applied thereto;

Figure 2 is a flat slab of concrete showing a plurality of these expansion joints placed in such position that an expansion joint is formed which prevents the passage of moisture through the joint between the slabs of concrete;

Figure 3 is an elevational view of a piece of material showing the fold lines marked thereon;

Figure 4 is an elevational view of a portion of the material showing a channel projecting upward therefrom;

Figure 5 is a side elevational view of an expansion joint formed, ready to be placed in a concrete structure;

Figure 6 is an elevational view of one end of the expansion joint showing the section projecting inward;

Figure 7 is a view similar to Figure 3 showing a flat piece of material with fold lines marked thereon, the channel in this section having a slightly flattened portion thereon;

Figure 8 is an elevational view showing the flattened section of rib;

Figure 9 is a side elevational view of the ex-

45

55

pansion joint shown in Figure 7 after being folded to position; and

Figure 10 is an elevational view showing the channel section in one end of the expansion joint 5 shown in Figure 9.

Referring now specifically to the drawings, and in which like reference characters refer to like parts throughout, a vertical concrete wall 15 is shown, which has a horizontal wall 16 integrally 10 formed therewith extending at right angles to the portion 15. An expansion joint, designated as a whole as 17, is provided in the end of the concrete sections 15 and 16 and against which similar concrete sections are formed in abutting relation in the construction of a wall for a flume, conduit, basement floor or the like, as may be desired. The expansion joint 17 (Fig. 3) is made up of a single piece of flat, flexible material such as copper, and has fold lines marked thereon, 15 lines 18 and 19 extending longitudinally of the expansion joint 17, with a center line 20 being provided, with transverse lines 21 and 22 and short diagonal lines 23 and 24 which register with the lines 21 and 22 at one side thereof and connect at the point of intersection with the longitudinal fold line 20. When the expansion joint 17 is folded along these lines, wing portions 25, 26 are formed at each side of the joint member, with a V-shaped channel section 26 therebetween, and is so folded that when the expansion joint member is finally formed (Fig. 1), the channel portion 26 on one end of the expansion joint member extends inward (the horizontal section in Fig. 1), while on the other end of the member the channel section 26 extends outward from the expansion joint member (the vertical portion shown in Fig. 1), with the spread of the V being comparatively narrow so that the wing portions 25 are embedded in the concrete, movement of the expansion joint member is permitted through the flexing of the channel section 26.

When these joint members are fashioned, the material is folded along the longitudinal fold line 20, which becomes the apex of the channel portion 26 of the joint member. The material is again folded along the longitudinal fold lines 18 and 19 whereby the wing portions 25 are formed, these portions extending generally parallel to the longitudinal direction of the concrete structure, 45 as shown in Figure 1, and are embedded in the concrete as it is formed. The walls of the channel section 26 are angularly positioned with respect to the wing portions 25, with the spread of the V-shaped channel section being of sufficient width to allow for contraction and expansion of the concrete. The strip of material is thereafter folded transversely along the fold lines 21 and 22 and the diagonal fold lines 23 and 24. Preferably, one end of the material in this form 50 has the apex of the V-shaped channel section extending in one direction while at the opposite side the apex thereof extends in the opposite direction. The apex of one of these channel sections extends into and centers at the bottom of the 55 channel portion 26 of the expansion joint member. In this way the material is folded so that the expansion joint is a continuous strip of material extending around the corners and, of course, the ends may be overlapped if it is desired to put in several sections of material in a 60 concrete structure.

In Figures 7 to 10, inclusive, a modified form of structure is shown. In this structure longitudinal fold lines 27 and 28 are provided centrally located with respect to the flexible member

making up the joint, while other longitudinal lines 29 and 30 are provided along which the material is folded along transverse fold lines 31 and 32 extending across the outer or wing portions 33, 34 of the member and along diagonal fold lines 34 and 35. These fold lines intersect a fold line 36 connecting the two fold lines 27 and 28, and which, when the material is formed, provides a channel section 37 having a flat portion 38 at one side thereof, but in which the channel section 37 extends in one direction on one end of the expansion joint member, and in the opposite direction at the other portion of the member, particularly as shown in Figure 9.

In Figure 2 is shown a form of device made into a rectangle for placing in a flat slab of concrete 39, for road work and the like. This form is of the same type as shown in Figure 1, with the exception, of course, that the dimensions of the expansion joint member are such as to conform to the flat slab and in which only a short portion of the expansion joint member is turned at an angle to form the vertical portions of the expansion joint extending from the top and bottom of the slab 39.

In operation of the device, it will be understood that these joint members are formed with appropriate tools on the job where the concrete is poured. They can be fashioned to fit the particular forms of concrete being poured and are placed in position with the concrete poured therearound, and thereafter the concrete joints are formed by packing in the usual manner by using some form of bituminous material between the ends of the concrete members, thus embedding the joint members in the concrete structure.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. An expansion joint for concrete structures comprising a unitary sheet of metal having its end portions folded at an angle to each other and into channel portions in one section, the channel section projecting inwardly and the other portion 50 having the channel portion extending outward.

2. An expansion joint for concrete structures composed of a unitary sheet of metal folded into channel sections with wings extending therefrom at an angle thereto having portions folded at an angle to each other with the channel section extending inwardly on one end of the section and outwardly at the opposite end.

3. An expansion joint member comprising a unitary sheet bent in a longitudinal direction to form a channel member intermediate the sides of the said member, and having wing members extending outward from the channel member on each side thereof and bent intermediate its ends to form portions at an angle to each other, the 60 said channel section extending in one direction in one portion of said member and in the opposite direction in the other portion of the said member.

4. An expansion joint member composed of a single sheet of foldable material having a V-shaped channel section extending longitudinally thereof, and wing portions extending outward from said channel section on each side thereof, the section being folded in a transverse direc- 75

tion intermediate its ends whereby one end is disposed at an angle to the other end, the apex of the V-section extending in one direction on one end of the section and in the opposite direction in the other end.

5. An expansion joint member composed of a single sheet of foldable material having a V-shaped channel section extending longitudinally thereof, and wing portions extending outward

from said channel section on each side thereof, the section being folded in a transverse direction intermediate its ends whereby one end is disposed at an angle to the other end to the apex of the V-section on one end, extending into 5 the trough of the V-section at the other end at the point where the section is bent in a transverse direction.

JOHN FOSTER OURY.
